UNITED STATES PATENT OFFICE

2,324,872

ADVERTISING SIGN

George W. Parker, Jr., Philadelphia, Pa., assignor
to Specialty Engineering Company, Philadelphia, Pa., a corporation of Pennsylvania

Original application December 1, 1938, Serial No.
243,327. Divided and this application October
24, 1940, Serial No. 362,508

8 Claims. (Cl. 40—129)

This invention relates to advertising signs, particularly to signs useful in connection with commercial vehicle bodies, the present application being a division of a co-pending application Serial No. 243,327 filed by me on December 1, 1938, now Patent No. 2,222,986.

My invention has for its primary object the provision of a sign of the kind referred to with incorporated attaching means, which is of simple construction, which lends itself to expeditious and economic manufacture as a metallic structure from standardized stock materials; and which, though relatively light in weight, is strong and sturdy for capacity to serve as a reinforcing tie member on the vehicle body wherewith it is used.

Another object of my invention is to afford in connection with a sign having the above attributes, auxiliary means for effectively sustaining it intermediate its ends, which means is to be likewise capable of ready and cheap manufacture from standard stock materials.

Other objects and attendant advantages will appear from the following detailed description of the attached drawings, wherein

Fig. 1 is a view partly in side elevation and partly in longitudinal section, of a metallic truck body together with a lengthwise-extending overhead advertising sign constructed in accordance with my invention.

Fig. 2 is a cross section of the organization taken as indicated by the angled arrows II—II in Fig. 1.

Fig. 3 is a detail longitudinal sectional view taken as indicated by the angled arrows III—III in Fig. 2 and showing how the sign is anchored at the front end of the truck body.

Fig. 4 is a detail sectional view taken as indicated by the arrows IV—IV in Fig. 1, and showing how the sign is supported intermediate the length of the truck body.

Fig. 5 is a detail view similar to Fig. 3 showing how the sign is anchored at the rear end.

Fig. 6 is a fragmentary view corresponding to Fig. 1 showing a modification in the construction of the sign.

In Figs. 1—5, the advertising sign of my invention is comprehensively designated by the numeral 15; and in order that the manner of mounting it may be more readily understood, I will first briefly describe the illustrated truck body, which is of the same construction as that featured in the co-pending application hereinbefore referred to, and formed wholly of metal. As shown, the truck body comprises a pair of later-

ally spaced Z section sills 16, and uprights or posts 17 of channel section which are equi-spaced in rows along opposite sides of the body and which rest on the inwardly-directed bottom flanges of the sills with their backs bearing against the vertical webs of said sills as shown in Fig. 2. At uniform intervals of the height of the body the uprights or posts 17 are connected by cross members 18 of invert channel section, whereof the ends extend beyond said posts, also as shown in Fig. 2; and to the ends of said cross members are secured side longitudinals or rails 19 of sheet metal with upturned rounded beads and with inwardly directed bottom flanges, which, together with oppositely-directed bottom flanges on the cross members 18, provide multiple retaining shelves for bottle cases C or the like, said shelves being accessible from opposite sides of the body for convenience of ready loading and unloading. The lowermost longitudinals 19 are formed as channels and are of substantially the same depth as the sills 16, for service as ornamental reinforcing side aprons for the body. Diagonally-arranged braces 20 connecting adjacent uprights 17 at opposite sides of the body add to the rigidity of the structure. At its front and rear ends the body is closed by walls 21 and 22 which extend somewhat above the uppermost cross members 19. The frames 25 of the walls 21 and 22 are formed from angle bars 23 and 24 bent to invert V shape with their side flanges directed inwardly; while the panels 25 and 26 of said walls are formed from sheets whereof the top and side edge margins abut the flanges of the frame angles as shown in Fig. 1.

The sign 15, with the construction of which the present invention is more especially concerned, extends lengthwise above the truck body in the longitudinal median plane of the latter. Fundamentally the sign consists of a frame with upper and lower parallel bars 27, 28 and an insert 29 of sheet metal, the upper bar 27 being bent downward at opposite ends for abutment thereagainst of the ends of the lower bar 28. From Fig. 2 it will be observed that the bars 27 and 28 are tubular, and slotted as at 30 and 31 to form an internal perimetric groove in the sign frame for reception of the edge margins of the panel 29. The bars 27 and 28 may be permanently connected together at the regions of abutment by welding, and the panel 29 secured to them by suitably spaced rivets such as shown at 32 in Fig. 3. At the front end of the sign, the down-turned portion of the upper frame bar 27 is extended somewhat below the lower

bar 28 as at 33 in Figs. 1 and 3, and inserted therein is a thimble shaped sleeve 35 whereof the circumferential flange rests upon the top of the frame angle 23 of the wall 21 at the forward end of the truck body. The sleeve 35 may be secured within the down-turned front end of the bar 27 by welding; and in turn secured within said sleeve in a like manner is a shank 36 which is adapted to extend downward through vertically aligned apertures in the crosswise portion of the angle bar 23 of the front end wall 21, in the corresponding uppermost cross member 18 of the truck body, and in an angle lug 37 affixed to the front wall panel 25 as shown in Fig. 2 and under-reaching said cross member. The lower end of the shank 36 is threaded to take a securing nut 38 which clamps against the lug 37; and a tubular spacer 39 surrounds said shank in the interval between the angle 23 and the uppermost cross member 18 of the truck body. At the rear end of the truck body, see Figs. 1 and 5, the sign frame bars 27 and 28 meet at a point beyond the back wall 22. Somewhat inward of this juncture of the bars 27, 28 a thimble 40 and a pendant shank 41 are welded to the lower bar 28, said shank passing through vertically-aligned apertures in the crosswise portion of the back wall frame angle 24, the corresponding uppermost cross member 18 at that end of said body and lug 42 secured to the panel 26 of said back wall, a securing nut 43 and a spacing sleeve 40 being here used for the same purpose as at the front end of the sign.

If desired the construction of the rear end of the sign 15 may be exactly like that at the front end, that is to say, the rear end of the upper bar 27 may be bent downward at right angles and extended below the lower bar 28 as at 45 in Fig. 6, provided with a thimble portion 46, a threaded shank 47, a securing nut 48, and an associated spacer sleeve 49.

Intermediate its ends the sign 15 is supported by a bracket which is shown in Figs. 1 and 4, and there generally designated by the numeral 50. This bracket 50 comprises an invert V shaped main bracing component 51 fashioned from round bar stock, whereof the ends of the legs are passed through apertures in one of the intermediate cross members 18 of the truck body. As shown in Fig. 4, the leg ends of the component 51 are threaded to take clamp nuts 52 with interposition of washer plates 53 which span the hollow of the cross member 18 at the bottom. The bracket 50 also comprises a smaller invert V component 55 which is disposed within the plane of the main component 51 and likewise fashioned from round bar stock with outwardly-extending apertured feet 56 for penetration by the ends of said main component 51. The supplemental component 55 is secured by means of clamp nuts 57 which threadedly engage the legs of the main component 51 and which bear downward upon the feet 56 of said supplemental component. The crotch of the main bracket component 51 is rounded to receive the upper bar 27 of the sign frame, which bar is held in fixed relation by means of the U bolt 58. To the lower bar 28 of the sign frame is welded or otherwise secured at the center, a threaded bolt 59 which passes down through an aperture in

the flattened central portion 60 of the bracket component 55; and nuts 61 are provided on the bolt 59 to clamp against the top and bottom of the raised medial portion of the support 55, whereby the sign is rigidly secured with capacity for adjustment to said bracket component.

From the foregoing it will be seen that I have provided an advertising sign of simple and inexpensive construction which is so mounted as to constitute an effective lengthwise top tie member which adds to the strength and rigidity of the truck body.

Having thus described my invention, I claim:

1. An advertising sign structure for use on a truck body, including a panel; and a transverse brace means having a central notch to engage over the top edge of the panel and side legs whereof the ends are adapted to penetrate the truck body for anchorage, and a crosswise member extending between the legs of the brace to support the lower edge of the panel.

2. The invention according to claim 1, in which a shank pendent from the lower edge of the panel engages into a central aperture in the crosswise member.

3. The invention according to claim 1, in which the transverse support is disposed medially of the ends of the panel; and in which said panel has pendent shanks at opposite ends thereof for anchorage in the truck body.

4. An advertising sign structure of the character described comprising a framed panel; and a transverse support including a main invert V shaped brace component whereof the vertex engages over the top edge of the frame, and a smaller invert V shaped brace component within said main component whereof the top or vertex constitutes a rest for the lower edge of the sign and whereof the legs are connected at their bottom ends to the leg bottoms of said main component.

5. An advertising sign structure according to claim 4, in which the legs of the auxiliary brace component have laterally extending apertured feet, and in which the leg ends of the main component are anchored in the apertures of the feet of said auxiliary component.

6. An advertising sign structure according to claim 4, including an anchoring shank pendent from the lower edge of the panel frame and engaged in an aperture in the auxiliary brace component.

7. An advertising sign structure according to claim 4, in which the transverse support is disposed medially of the panel frame, and in which said frame has pendent anchorage shanks at opposite ends thereof.

8. An advertising sign structure according to claim 4, in which the sign panel frame is formed from two one-piece components, one of generally invert U configuration providing the top horizontal and end portions of the frame, and the other being straight to constitute the lower horizontal of the frame and having its ends secured in abutting relation to the end portions of the first component, said frame being perimetrically slotted internally for reception of the panel edges.
